UNITED STATES PATENT OFFICE

HAROLD F. ELLIOTT, OF CAMDEN, NEW JERSEY, ASSIGNOR TO VICTOR TALKING
MACHINE COMPANY, A CORPORATION OF NEW JERSEY

DESIGN FOR A RADIOPANEL

Application filed September 20, 1929. Serial No. 32,807. Term of patent 14 years.

To all whom it may concern:

Be it known that I, HAROLD F. ELLIOTT, a citizen of the United States of America, and a resident of Camden, New Jersey, have invented a new, original and ornamental Design for Radiopanel, of which the following is a specification, reference being had to the annexed drawing, forming a part thereof and

which shows a perspective view of a cabinet embodying my new design.

I claim:

The ornamental design for a radiopanel as shown.

In testimony whereof I have signed this specification.

HAROLD F. ELLIOTT.
